PORTABLE ATTACHMENT TRAY FOR A DESK DRAWER

Jo Ann P. Sciarrone, 5046 Bayou Vista,
Houston, Tex. 77088

Filed Nov. 17, 1972, Ser. No. 307,602

Term of patent 14 years

Int. Cl. D7—99

U.S. Cl. D7—38

FIG. 1 is a rear perspective view of a portable attachment tray for a desk drawer showing my design;

FIG. 2 is a front perspective view thereof; and

FIG. 3 is a perspective view of the article in position for use, the dotted line showing the desk fragment being for illustrative purposes only.

I claim:

The ornamental design for a portable attachment tray for a desk drawer, substantially as shown and described.
